UNITED STATES PATENT OFFICE.

FREDERICK NISHWITZ, OF BROOKLYN, NEW YORK.

IMPROVEMENT IN HARVESTERS.

Specification forming part of Letters Patent No. 95,373, dated September 28, 1869.

To all whom it may concern :

Be it known that I, FREDERICK NISHWITZ, of Brooklyn, in the county of Kings and State of New York, have invented certain new and useful Improvements in Harvesters, of which the following is a full, clear, and exact description:

The invention herein claimed relates to a novel method, hereinafter set forth, of constructing the frame and gearing of a harvester.

In the accompanying drawings all my improvements are represented as embodied in a single machine.

It is obvious, however, that some of the improvements may be used without the others, and may also be adapted to machines differing in construction from that herein shown.

Figure 1 represents a plan or top view of my improved machine. Fig. 2 represents a vertical longitudinal section through the same at the line $\alpha\alpha$ of Fig. 1. Fig. 3 represents a view in elevation of the same as seen from the rear, with the cutting-apparatus folded up vertically; Fig. 4, a plan view of the gear-frame; Fig. 5, a front view; and Fig. 6, a plan view of a portion of the pitman and cutter detached, showing the details of their construction.

In this instance, two main driving and supporting-wheels, A A', turn loosely on a common axle, B, with which they are connected by backing-ratchets of any usual well-known construction. The axle revolves in pipe-bearings in a frame, C, arranged between the wheels, and projecting mostly in front of the axle B. A spur-wheel, D, keyed fast on the main axle, drives a spur-pinion, d, on a counter-shaft, e, behind and above the main axle. A spur-wheel, E, on this shaft, drives a corresponding pinion, f, on a shaft, f', parallel with and below the counter-shaft. A bevel-wheel, F, on this shaft, drives a corresponding pinion, g, on a crank-shaft, G, driving the cutters by a crank and pitman, in the usual way. The main frame, it will be observed, has the bearings for the main axle and of the shafts e f', as well as the shield T, for protecting the balance-wheel and pitman, all cast in one piece. The shafts e and f' are keyed fast in their sockets in the frame, while the gear-wheels d, E, f, and F all run loosely on their shafts, and can consequently be removed by driving the shafts

endwise out of their sockets in the main frame, which mode of construction renders it easy at any time to remove or replace the gear-wheels.

The construction of the main frame is clearly shown in Fig. 4, in which the black lines represent the frame, the blue lines the shafts, and the red lines the gearing. A cover, S, for the gearing, which also serves as a foot-board for the driver, is pivoted to play vertically around the shaft e, so as to afford ready access to the gearing. The supports n, of the driver's seat, are likewise pivoted on the shaft e, which mode of construction diminishes the labor of putting the parts of the machine together. A tongue, H, is secured by a bolt, h, to a plate, H', upon which it may be adjusted up or down by a bolt, h¹, taking into one of a series of holes in the front of the plate. A socket, h², on the rear end of this plate, fits on a pivot, I, on the front of the gear-frame, so as to allow the tongue to play freely vertically. The tongue extends back of its pivot I, and its rear end is slotted vertically. A transverse pin in this slot is embraced by a loop, j, attached to an arm, j', on a lifting-lever, J, pivoted to the main axle B. A pawl, K, pivoted to the lifting-lever, takes into ratchets e on the gear-frame, to hold the gear-frame at any desired elevation. This pawl is released by backing the lever slightly, and then shoving down a rod, k, sliding endwise in a groove in the lifting-lever, and bearing on the rear end of the pawl. The finger-beam L is fastened securely, at its heel end, to a shoe, L', which extends much farther in front of the finger-beam than usual, and is provided with lugs l, between which down-hangers or coupling-arms I I' are pivoted by a rod, l', which is bent up at its forward end, and bolted to the front end of the tongue-plate H', thus serving both as a pivot and a brace. The rear coupling-arm I, it will be observed, in this instance, is inserted in a socket in the front of the gear-frame, and is likewise secured to the rear end of the tongue-plate, and forms the pivot on which the tongue vibrates. The front coupling-arm and brace l' are likewise secured to and vibrate with the tongue-plate.

By this mode of construction, the raising and lowering of the tongue correspondingly vibrates the shoe, and thus varies the angle of the grounds relatively to the ground.

A link, m , is pivoted, at its lower end, to the shoe L' , outside of and below its pivot l' , while its upper end is attached to a lever, M , vibrating in a vertical plane on the front coupling-arm I . By drawing back this lever, the link m swings the shoe around its pivot l' , and thus lifts the divider-end of the finger-beam. A friction-roller, m^1 , on the lever-plate, traverses on the tongue-plate, and prevents the friction of the tilting-lever against the tongue. A cord or chain, m^2 , is secured at one end to the main frame, and at the other to the lever M . This cord prevents the forward movement of the lever M , and consequently prevents the divider-end of the finger-beam from falling below a given point, while leaving it free to rise and move the lever backward. When the finger-beam is vertical, the lever M takes into notches m^3 on the side of the lifting-lever, and is firmly held there. A seat, N , for the driver, is mounted on standards n , pivoted to vibrate on the counter-shaft e . An arm, n' , fixed on one of the standards, is connected by a link, N' , with the tongue-plate in front of and above the pivot I . The seat is thus moved back and forth, when the gear-frame is raised or lowered by the hand-lever J . The shipping-lever O' is operated by a link, O , coiled around the rod N' , so as to be pushed backward or forward by the driver's foot, to throw the mechanism into or out of gear. A flanged collar, o , on this lever, is provided with internally-projecting inclines, o , which bear against corresponding inclines on the main frame, and thus moves the gear-wheel E endwise on its shaft, to throw the mechanism into or out of gear. The cap x , of the crank-shaft bearing, is hinged, and made to fit between the nuts which hold the bearings in place, and thus prevents them from working loose.

In Fig. 1, the cover is shown in red, as thrown back, to permit the bearings to be oiled.

Figs. 5 and 6 show nut-locking device hinged to the pitman, and held over its nuts by pins,

to prevent the motion of the pitman from jarring the nuts out of place.

The spring-stop l' is pivoted, near its forward end, to the shoe, while its rear end is bent down, so as to catch against the flange of the shoe, and prevent the cutter-bar from dropping out of its guides when the finger-beam is raised on end. When the cutter-bar is to be removed, the rear end of the spring is lifted and turned out of the way, as shown in red in Fig. 1.

What I claim as my invention, and desire to secure by Letters Patent, is—

1. The combination, with the main frame and removable shafts, of gear-wheels revolving loosely on the shafts, all constructed as described, to permit the gearing to be removed or replaced without removing any portion of the frame.

2. The combination of the spur-wheel on the main axle, the loose spur-gears on the counter-shaft, the loose spur-gears on the shaft f' , the bevel-wheel on the same, and the crank-shaft crossing the main axle, all constructed and arranged for joint operation, as set forth.

3. The combination of the shipping-lever, constructed as described, and operated by a foot-lever sliding on the rod which connects the tongue and driver's seat, substantially as set forth.

4. The arrangement on the counter-shaft, as described, of the gear-wheels, the shipping-lever, and the platform-cover.

5. The combination with the shoe, of the pivoted spring-stop, operating as described, to prevent the cutter from dropping out when the divider-end of the finger-beam is elevated.

6. The combined foot board and gear-cover, arranged to vibrate about the countershaft, as set forth.

In testimony whereof I have hereunto subscribed my name.

F. NISHWITZ.
